FOUNTAIN PEN

Eugene K. Werner, New York, N. Y.

Application February 14, 1934, Serial No. 711,103

6 Claims. (Cl. 120—42)

This invention relates to new and useful improvements in writing instruments, and more particularly it pertains to such devices as are commonly known as fountain pens.

5 In the fountain pen as generally constructed, ink is carried in an ink sack from which it is delivered through a feed bar to the writing point during use of the pen. Such pens, when the ink supply becomes exhausted, are useless for writing purposes until the ink supply is renewed by refilling the ink sack. The ink sack being of relatively small capacity, the supply does not last a great length of time and it often happens that the supply becomes exhausted and the pen will 15 not write just at a time when ink to replenish the supply is not available.

It is an object of the present invention to provide a novel construction of fountain pen in which, with the use of water, a writing fluid is 20 formed directly in the pen, thus making it necessary to supply, except at long intervals, only water, which is always available, when the supply of writing fluid becomes exhausted.

Another object of the invention resides in a 25 novel and simple construction whereby the pen may be easily operated without removing any of the parts and requiring no special tools for the purpose.

With the above and other objects in view, reference will be had to the accompanying drawing wherein the invention is illustrated in its preferred form, and in which,

Figure 1 is a view in elevation of a fountain pen constructed in accordance with the present invention,

Figure 2 is a longitudinal sectional view partly broken away, the view being on an enlarged scale,

Figure 3 is a view similar to Figure 2, illustrating the construction to a greater degree of detail,

40 Figure 4 is a detail sectional view, taken on the line 4—4 of Figure 1, the view being taken on an enlarged scale, and;

Figure 5 is a distended perspective view.

Referring in detail to the drawing, the reference character 10 designates the barrel of the pen. This barrel 10 has one of its ends open, and at its open end it is provided with an internal screw thread 11, and an external screw thread 12. The external screw thread 12, is adapted to engage the internal thread 14, of the cap 15, when the latter is placed upon the writing end of the pen.

The water sack is designated 16, and it is adapted to be carried within the barrel 10. It is mounted within the barrel 10, by means of a tubular

member 17, the construction of which is more clearly illustrated in Figure 5. This tubular member 17, has an extension 18, which receives the water sack 16, as more clearly shown in Figure 3. Adjacent the extension 18, there is an 60 enlarged externally threaded section 19, the threads 20, of which are adapted for engagement with the internal threads 11, of the barrel 10, to secure the tubular member 17, in said barrel, the tubular member 17, having an annular shoulder 65 21, for engagement with the open end of the barrel 10. The tubular member 17, also has a threaded portion 22, and it is provided with an elongated slot or opening 23, the purpose of which will be hereinafter described. 70

The reference character 24, designates the feed bar of the pen, and except for the fact that it is provided with an elongated recess 25, it may be of substantially conventional construction. The feed bar is adapted to be mounted within 75 the tubular member 17, and is held therein preferably by friction, the writing point 26, being frictionally held between the feed bar and the tubular member 17.

In assembling the several parts, the feed bar 80 24, is so positioned within the tubular member that the recess 25, will be in registration with the elongated opening 23, in the tubular member 17, which permits the insertion into the recess 25, of an ink stick 30. This ink stick 30, is of such a 85 character as to be readily soluble in water to provide a writing fluid which will be delivered by the feed bar to the writing point when the pen is in position for use.

Means is provided to retain the ink stick 30, 90 within the recess 25, of the feed bar and this means preferably consists of a sleeve 31, internally threaded as at 32 for engagement with the external thread 22, of the tubular member 17. When screwed home, the inner or rear end of the 95 sleeve 31, engages the forward face of the shoulder 21, and closes the elongated opening 23, sufficiently to retain the ink stick in position within the recess 25, of the feed bar 24. A washer 34, may be employed at this point to provide 100 a fluid tight joint between the inner end of the sleeve and the shoulder 21.

With the several parts in the position in which they are shown in Figure 3, water in the sack 16, is fed through the feed bar 24, to the writing point 26. In its passage to the writing point, it passes in the presence of the ink stick 30, which, being soluble, provides a writing fluid when it is delivered to the writing point. If the supply of writing fluid becomes exhausted, it is only nec- 110

essary to refill the sack 16, with water in the same manner that it is refilled with ink in the ordinary pen, and water being always available, a pen constructed in accordance with the present invention is never, so long as there is an ink stick 30, within the receptacle 25, rendered even temporarily unusable.

The ink sticks are of such character that one will, under ordinary writing conditions, supply writing fluid sufficient for several months' use of the pen. A supply of ink sticks may be carried in the pen, and for this purpose, I have shown the rear end of the barrel 10, as provided with a compartment 40, closed by a screw cap 41, although this compartment may as well be provided in the closed end 43, of the cap 15, if desired.

When it is desired to place an ink stick in the receptacle 25, of the feed bar, it is only necessary to unscrew the sleeve 31, as illustrated in dotted lines in Figure 3, in which position, an ink stick may be freely positioned within the recess 25, of the feed bar.

From the foregoing, it will be apparent that the invention provides a new and novel construction of fountain pen wherein water, which is always available, may be used instead of ink, thus rendering the pen at all times available for use.

While the invention has been herein illustrated in its preferred form, it is to be understood that it is not to be limited to the specific construction herein shown, and that it may be carried out in other forms which rightfully fall within the scope of the appended claims.

Having thus described the invention, what is claimed as new and what it is desired to secure by Letters Patent of the United States, is:

1. In a writing instrument of the type described, a feed bar having a recess therein and a side opening providing access to said recess, means for supplying fluid to said recess, means for discharging fluid from said recess, and means for closing the side opening of the feed bar.

2. In a writing instrument of the type described, a feed bar having a recess therein and an opening providing access to said recess and fluid feed passages leading to and from said

recess, and means surrounding the feed bar for closing the opening which provides access to the recess.

3. In a writing instrument of the type described, a feed bar having a recess therein and an opening providing access to said recess and fluid feed passages leading to and from said recess, and a sleeve surrounding the feed bar and movable longitudinally thereof to open and close said opening.

4. In a writing instrument of the type described, a feed bar having a recess therein and an opening providing access to said recess, a threaded portion on the exterior of said feed bar, a sleeve surrounding the feed bar, and a threaded portion on said sleeve adapted for threaded engagement with the threaded portion of the feed bar whereby upon rotation of the sleeve, the same will be moved longitudinally of the feed bar to open and close the opening of the recess in the feed bar.

5. A feed bar for fountain pens comprising a body portion having a recess therein and an opening providing access to said recess, an annular flange on said feed bar closely adjacent one end of said recess and providing an annular shoulder, and a sleeve surrounding said feed bar and movable longitudinally thereof to open and close the afore-mentioned opening and having engagement with said shoulder when in position to close said opening.

6. A feed bar for fountain pens comprising a body portion having a recess therein and an opening providing access to said recess, an annular flange extending around said feed bar to provide an annular shoulder thereon adjacent one end of the recess, a threaded portion on the feed bar adjacent the other end of the recess, a sleeve surrounding said feed bar, said sleeve having an internal thread for engagement with the thread on the feed bar whereby upon rotation of the sleeve, it will be moved longitudinally of the feed bar to open and close said opening, one end of said sleeve having engagement with said shoulder when the sleeve is in position to close the opening.
